UNITED STATES PATENT OFFICE.

FRANK YOKEL, OF PITTSBURGH, PENNSYLVANIA, ASSIGNOR TO PITTSBURGH LAMP, BRASS & GLASS COMPANY, OF PITTSBURGH, PENNSYLVANIA, A CORPORATION OF NEW JERSEY.

INVERTED INCANDESCENT GAS-LAMP.

1,254,105.

Specification of Letters Patent. Patented Jan. 22, 1918.

Application filed August 11, 1915. Serial No. 44,865.

To all whom it may concern:

Be it known that I, FRANK YOKEL, a citizen of the United States, and resident of Pittsburgh, in the county of Allegheny and 5 State of Pennsylvania, have invented certain new and useful Improvements in Inverted Incandescent Gas-Lamps, of which the following is a specification.

This invention relates to improvements in 10 incandescent gas lamps, and more particularly to those of the inverted type.

The objects of my invention are to provide a structure of this type which is simple and efficient in operation, readily assembled, 15 durable in construction, and which can be manufactured at a relatively low cost.

To these and other ends, the nature of which will be readily understood as the invention is hereinafter disclosed, my invention 20 consists in the improved construction and combination of parts hereinafter duly described, illustrated in the accompanying drawing, and more particularly pointed out in the appended claims.

25 In the accompanying drawings, in which similar reference characters indicate similar parts in each of the views,

Figure 1 is a side elevation of a lamp of this type with parts broken away to illustrate certain relative positions.

Fig. 2 is a vertical sectional view of the same.

Fig. 3 is a vertical section taken at right angles to Fig. 2.

35 Lamps of this type, and especially those of the inclosed mantle type, are generally of a structure expensive to manufacture, the requirements relative to protection of the lamp against drafts, etc., necessitating the 40 use of complicated structures, the production and assembling of which involve comparatively large expense.

I have found, through various tests, that 45 many of the difficulties for which protection was provided could be overcome by various changes in the construction of the lamp body, and in a manner which greatly reduces the cost of production. For instance, it is well known that by preheating the air 50 which is employed in admixed relation with the gas, more efficient service is had. To obtain this result, it is the practice to subject the air conduit to the action of the products of combustion. This preheating 55 action, however, must be in such form as

to prevent the products from entering the air being admitted, as such products would materially affect the combustion of the mixture, not only affecting the candle power of the lamp, but also tending to provide a 60 smoky action; hence, it has been the practice to provide special structural details to take care of this difficulty. As these special details have to be provided in such manner as to properly coördinate with the remainder of the lamp to produce a proper 65 effect both in operation and appearance, the development tendency has been along lines leading to an increase rather than a reduction in the complicated character of the 70 structures, thereby tending rather to increase the cost of production than to decrease it.

During my experiments, I have found 75 that this segregation of the products from the inflowing air can be effected without the use of special complicated structures, and at the same time, obtain the advantages due to preheating the air. This fact enables me to change the general structural arrangement of the lamp in a manner to greatly simplify its structure and at the same time produce the desired coördination in operation and appearance, these changes greatly decreasing the cost of manufacture. A preferred construction for obtaining these 80 results is shown in the drawings, and is now 85 described.

10 indicates the gas admission element having a suitable admission control, indicated at 11, a regulating device 12, and a pilot tube 13, these being of well known construction. The element 10 is mounted at the upper end of the mixing tube 14, the latter communicating with the burner, 95 shown at 15 as in the form of an incandescent mantle of the inverted type.

As shown, the connection between the mixing tube 14 and element 10 is provided by a member 16 threaded to both of these 100 parts, said member 16 having openings 16^a at diametrically opposite sides, these openings having a suitable circumferential length and preferably extending above and below the point of gas exit from element 105 10. Mounted on the periphery of member 16, is a sleeve 16^b provided with a plurality of axially-extending narrow slots 16^c, these slots being arranged in two series diametrically spaced apart. The sleeve is rotatably 110

adjustable on the member 16, being held in adjusted position by means of a set screw 16^a, thus enabling a desired number of slots 16^c to be exposed opposite the openings 16^a.

5 This member 16 and sleeve 16^b form the air-admission element leading to the mixing tube and controllable as to amount by the adjustability of the sleeve 16^b.

The casing for the lamp is provided in 10 the form of a number of parts, each comparatively simple in structural form and readily manufactured, these members, when assembled, providing the desired result, the assemblage being carried by the mixing tube. The general casing members are indicated at 17, 18, 19 and 20.

The member 17 is of cup-shape form, its bottom 17^a being imperforate excepting for the substantially central opening provided 20 for the passage of the mixing tube 14 and the opening for the passage of the pilot burner tube. The side walls of the member 17 are flared outwardly, being provided with a shoulder 17^b adjacent the plane of the bottom 17^a. The upper edge of this member 17 is preferably bent inwardly as shown, thus providing a rigid formation at the point of greatest diameter of this member.

Members 19 and 20 are flared in opposite 3: directions and connected together at the points of greatest diameter, these members combinedly forming the lower portion of the conduit for the products of combustion and the support for the inner and outer 35 globes, member 19 being formed with a diametrically extending plate 19^a having down-turned flanges 19^b, said plate having openings for the passage of the mixing tube and of the pilot tube. The member 20 carries 40 an annular recess which is adapted to receive an annulus 20^a on which the inner globe 21 is supported. Said member also carries the means for securing the outer globe 22 in position. The member 19 is also 45 provided with a shoulder 19^c.

Member 18 is cylindrical, being provided at diametrically opposite sides with axially-extending narrow elongated slots 18^a. This member is adapted to be positioned between 50 members 17 and 19, the opposite ends of member 18 abutting the shoulders 17^b and 19^c, respectively.

The casing is assembled in the following manner: As shown more particularly in 55 Figs. 2 and 3, the lower end of the member 16 provides a shoulder 16^c with respect to the mixing tube. Mounted on the mixing tube and adapted to abut against said shoulder is a cross bar 23 having an opening for 60 the passage of the pilot tube and having its ends provided with projecting portions 23^a, the lower plane of which is spaced from the lower plane of the bar 23, these projecting portions being adapted to abut against the 5 inner periphery of member 17 opposite the

shoulder 17^b, as shown more particularly in Fig. 2.

After this bar 23 is slipped over the bare mixing tube, member 17 is passed on to this tube and moved into contact with the projecting portions 23^a. The member 18 is then slipped over the tube with its upper end in contact with shoulder 17^b, after which the unit formed of members 19 and 20 is slipped on to the tube to bring shoulder 19^c into 70 contact with the lower end of member 18. A cross bar 24 substantially similar to cross bar 23 is then slipped into position, its projecting portions 24^a contacting with the inner wall of member 19 opposite shoulder 19^c. 80 A short length of tubing 25 is then placed on the mixing tube, after which a nut 26 is threaded onto the tube, this nut serving to clamp the casing together, the clamping pressure being provided by tubular member 25 acting on cross bar 24, the pressure being resisted by cross bar 23 which is held in position by shoulder 16^c.

After the burner fixture and pilot burner have been placed in position, the mantle and 90 the inner and outer globes are positioned in the usual manner.

As will be readily understood, this arrangement of the casing is simple and of such form as to be readily assembled with a 95 minimum number of parts and threaded connections. The conduit for the products of combustion is provided by members 18, 19 and 20, this conduit being closed at its upper end by the bottom 17^a of member 17, the outlet for the products of combustion being through the slots 18^a. By this arrangement, the products are led directly into contact with the bottom 17^a which is thereby heated and acts to heat the air which may be immediately above the bottom.

As shown, the air inlet ports are spaced a short distance above the bottom 17^a, the major portion of the length of these ports being below the top plane of member 17. 110 Consequently, the cup-shaped formation of said member 17 provides a member which tends to isolate the air immediately above the bottom 17^a, causing it to rise, somewhat in the nature of an envelop, in proximity to the air-admission ports, the air supplied to the mixing tube coming from this source, the remainder simply passing upwardly along the exterior of the fitting 10.

While the air inlet ports 16^c extend below the top plane of member 17, these ports are not located within the casing but external of it, no portion of the casing acting to restrict free access of air to these ports, the flared portion 17 acting to carry the products of combustion outwardly to a point sufficiently spaced from the inlet ports as to practically eliminate the possibility of these products entering the point of supply of air for these ports.

As will be readily understood, the products of combustion, being of a higher temperature than the surrounding air into which they discharge through slots 18^a, will 5 pass upwardly after their exit through slots 18^a, the particular cross-sectional formation of member 17 tending to force these products outwardly so that passing the upper plane of member 17, they will be spaced a 10 considerable distance from the air admission ports and entirely without the envelop of heated air provided by the bottom 17^a. Consequently, the upward travel of the envelop will tend to draw the products upward above 15 the plane of the air admission ports and therefore away from such ports. However, the ability to produce this action is necessarily dependent on the supply of air to produce this envelop and at the same time 20 supply the air for the admixture with the gas, and this must be secured from without member 17.

To enable this result to be obtained, the 25 particular arrangement of slots 16^c and 18^a are provided. As before pointed out, these slots are arranged on diametrically opposite sides of the members in which they are formed. The slotted portions are of a predetermined circumferential length, these 30 lengths being such that when the parts are assembled, a plane connecting the slots 16^c will intersect at approximately right angles a similar plane connecting slots 18^a, the circumferential length of the slotted portions 35 being such that the slots 18^a will be out of vertical alinement with any portion of the slots 16^c. Consequently, the upwardly-flowing currents external of member 17 will be made up of alternate currents of air heated 40 by the exterior of the conduit and currents provided by the products of combustion. Since the air admission ports are arranged opposite the unvitiated air currents, it will be readily understood that even though 45 these outer currents are partially diverted inwardly into the member 17, the supply for the air admission ports will be provided by the unvitiated air, those portions of these 50 ascending currents carrying the products of combustion being opposite blank portions of the sleeve 16^b. Consequently, the supply of air is free from products of combustion.

By thus staggering the products outlet 55 and the air inlet, and by the use of the member 17, I am able to obtain the desired pre-heating action on the air to be supplied, and at the same time retain this air free from vitiation by the products, without the use of any special conduit or other structure, the 60 member 17 not only performing a useful function in this respect but, as shown in Fig. 1, giving an ornamental appearance to the sing as well. As before pointed out, the particular arrangement shown enables 65 the construction to be provided by the use

of but few parts of a simple character, thereby greatly reducing the cost of manufacture of the complete lamp without, however, sacrificing any of the material features which are essential in providing the 70 maximum efficiency.

While I have herein shown and described a preferred way in which my invention may be carried out, it will be readily understood that changes and modifications therein may 75 be required or desired to meet the exigencies of use, and I reserve the right to make any and all such changes and modifications as may be found necessary or desirable in so far as the same may fall within the spirit 80 and scope of the invention as expressed in the accompanying claims.

What I claim is:

1. In incandescent gas lamps of the inverted type, gas and air admission means, a 85 mixing-tube, a burner, a sectional casing forming a conduit for the products of combustion and including outer sections and an intermediate section encircling the mixing-tube, said intermediate section having diametrically disposed outlet ports, a diaphragm in the conduit separating the intermediate and the outer sections, diametrically extending members mounted on the mixing-tube, and means on the mixing-tube coöperating with said members for clamping the 90 sections together. 95

2. In incandescent gas lamps of inverted type, gas and air admission means having diametrically disposed air inlet ports, a mixing-tube, a burner, a sectional casing forming a conduit for the products of combustion and including outer sections and an intermediate section encircling the mixing-tube, said intermediate section having diametrically disposed outlet ports, said inlet and outlet ports being positioned on planes intersecting each other at right angles, a diaphragm in the conduit separating said ports, diametrically extending members mounted 100 on the mixing-tube, and means on the mixing-tube coöperating with said members for clamping the sections together. 105

3. In incandescent gas lamps of the inverted type, air and gas admission means, a 115 mixing tube secured thereto to provide a shoulder at the lower end of said means, a casing for the products of combustion formed of sections adapted to encircle the mixing tube, the outer sections having members extending diametrically across the conduit with the upper member acting to limit the conduit length, a cylindrical member mounted between and positioned by said outer members, and means on said mixing 120 tube for clamping said sections together, said shoulder forming an abutment operative in the clamping action. 125

4. In incandescent lamps of the inverted type, air and gas admission means, a mixing 130

4
tube secured thereto to provide a shoulder at the lower end of said means, a casing for the products of combustion formed of sections adapted to encircle the mixing tube, the outer sections having members extending diametrically across the conduit with the upper member acting to limit the conduit length, a cylindrical member between and positioned by said outer members, and means on said mixing tube for clamping said sections together, said means including a cross bar adapted to contact with said shoulder

above said diaphragm, a cross bar below the top plane of the opposite outer member, a sleeve on said mixing tube below said latter cross bar, and threaded means below and in contact with said sleeve. 15

In testimony whereof I affix my signature in presence of two witnesses.

FRANK YOKEL.
